(57) CLAIM

I claim the ornamental design for a non-electric coffee grinder, as shown and described.

DESCRIPTION

The file of this patent contains at least one drawing/photograph executed in color. Copies of this patent with color drawings will be provided by the Office upon request and payment of the necessary fee.

FIG. 1 is a top, front, left side perspective view of a non-electric coffee grinder embodying my new design without a logo;

FIG. 2 is a right side elevational view thereof;

FIG. 3 is a left side elevational view thereof;

FIG. 4 is a front elevational view thereof;

FIG. 5 is a rear elevational view thereof;

FIG. 6 is a bottom plan view thereof;

FIG. 7 is a top plan view thereof;

FIG. 8 is a top, front, left side perspective view of a non-electric coffee grinder of a second embodiment of my new design with a logo;

FIG. 9 is a right side elevational view thereof;

FIG. 10 is a left side elevational view thereof;

FIG. 11 is a front elevational view thereof;

FIG. 12 is a rear elevational view thereof;

FIG. 13 is a bottom plan view thereof; and,

FIG. 14 is a top plan view thereof.

The “COMANDANTE” logo and word depicted in FIGS. 8 and 10 and the design mark depicted in FIGS. 8 and 10 forming part of the claimed design are registered trademarks owned by Bernd Braune, the Applicant for the claimed design.

The dashed boundary lines in FIGS. 1, 6-8, 13 and 14 show unclaimed boundaries between claimed and unclaimed subject matter.
